BEDSPRING

Charles J. Elder, Muncie, Ind., assignor to The Moore Company, Muncie, Ind., a corporation of Indiana

Application June 19, 1943, Serial No. 491,437

7 Claims. (Cl. 5—276)

My invention relates to bed springs, and more particularly to that type of bed spring which embodies a plurality of rows of compression springs. In certain types of such bed springs it is common to associate with the upper turns of the compression springs a series of strips of sheet metal which extend across the spring assembly transversely thereof and which are anchored to the upper turns of the compression springs.

It is the object of my invention to improve and cheapen the construction of a bed spring of the type just referred to.

In carrying out my invention, I associate with each row of compression springs a pair of sheet-metal strips which extend over the upper end turns of such compression springs. The two sheet-metal strips associated with each row of the springs are held in spaced relationship relative to each other by sheet-metal cross-pieces, while each of such metal strips is connected by a series of tension springs with the adjacent sheet-metal strip associated with the adjacent row of compression springs. The tension springs just referred to are provided at their ends with hooks which pass through holes in the sheet-metal strips and embrace the end turn of compression springs in order to anchor such end turns to the metal strips and the tension springs to the metal strips.

The accompanying drawing illustrates my invention: Fig. 1 is fragmental plan view of a spring assembly; Fig. 2 is a view similar to Fig. 1 but on an enlarged scale; and Fig. 3 is a vertical section on the line 3—3 of Fig. 2.

The spring assembly shown in the drawing includes a plurality of transverse rows of coiled compression springs 10 supported in any desired manner from a base frame (not shown). The upper end turns of the springs 10 lie substantially in a common plane which also contains a border frame 11 secured to the upper end turns of marginal springs 10 as by means of rivets 12.

Associated with each transverse row of springs 10 are a pair of sheet-metal strips 15 held in spaced relation by sheet-metal cross members 16 secured to the two strips 15 as by means of rivets 17. The spacing of each pair of sheet-metal strips 15 is desirably less than the diameter of the end turns so that they extend chordally across the upper end turn of each spring 10 in the row with which they are associated. At the points where each strip 15 intersects the upper end turns 18 of the compression springs 10 the strip is provided with openings 19, desirably in the form of longitudinally extending slots.

Acting between adjacent strips 15 associated respectively with adjacent transverse rows of compression spring 10 are a series of helical tension springs 21. Each of these tension springs is provided at each end with a hook 22 conveniently formed by bending a portion of the end turn of the tension spring approximately at right angles as indicated at 23 in Fig. 2. The hooked ends 22 of the springs 21 extend through the openings 19 and embrace the end turn 18 of the associated compression spring 10 to anchor such end turn to the associated strip 15.

In addition to the holes 19 located at the points where each strip 15 intersects an end turn 18, the strips 15 may be provided between adjacent compression springs of a row with one or more additional holes 19, as will be clear from Fig. 1, and additional coil springs 21 may have their hooked ends engaged in such holes.

In the transverse row of compression springs 10 at each end of the assembly, the upper end turns 18 of the springs are connected directly to the border frame 11, as above indicated. Accordingly, only one of the strips 15 is used in association with each end row of compression springs 10, as will be clear from Fig. 1. If desired, this single strip 15 may be connected to the end of the border frame 11 by means of cross members 16.

In addition to the tension springs 21 which extend longitudinally of the spring-assembly between adjacent transverse strips 15, I may employ similar tension springs 25 acting between the upper turns of adjacent springs 10 in each transverse row. These springs 25 serve to take up lost motion transversely of the spring assembly and to increase the resilience of the spring assembly.

In assembling the bed spring, a sheet-metal strip 15 is laid over the end turns of a row of compression springs, and the hooks 22 of a series of tension springs 21 are then engaged with the strip 15 and the end turns 18 to anchor the strip to such end turns. In applying each of the tension springs 21, it is held in a generally vertical position and its hook inserted through the slot 19. Thereafter, the spring 21 is rotated to a horizontal position and its hook 22 forced over the wire of the end turn 18. By bending the extreme end of the hook 22 out of the hook-plane, as indicated at 26 in Figs. 2 and 3, the operation of snapping the hook over the wire of the end turn 18 is facilitated. Desirably, the outer edge of each of the slots 19 is notched to make the slot of a general T-shape so that when the

assembly is complete and the spring 21 under tension, the hooks 22 will be located in a definite position along the respectively associated slots 19.

If desired, the hooks 22 at the ends of each spring 21 may be so relatively disposed in reference to the spring axis that in the assembly the springs 21 will be subjected to a slight torsional stress. This tends to take up lost motion, to hold the end turn 18 of each compression spring 10 tightly against the under surface of the strip 15, and to prevent noise.

I claim as my invention:

1. In a bed spring, a plurality of rows of coiled compression springs having their upper end turns located substantially in a common plane, a pair of spaced sheet-metal strips associated with each such row of compression springs, said pair of strips extending longitudinally of the associated row of compression springs and chordally of the upper end turns thereof, each of said strips being provided with longitudinal slots at points where it crosses the end turns of the compression springs, tension springs interconnecting adjacent strips of adjacent pairs, each of said tension springs being provided at each end with a hook which passes through one of said slots and also embraces the associated end turn of a compression spring, said slots having a length greater than the overall width of said hooks, whereby each hook can be bodily inserted through its associated slot.

2. In a bed spring, a plurality of rows of coiled compression springs having their upper end turns located substantially in a common plane, a pair of spaced sheet-metal strips associated with each such row of compression springs, said pair of strips extending longitudinally of the associated row of compression springs and chordally of the upper end turns thereof, each of said strips being provided with openings at points where it crosses the end turns of the compression springs, tension springs interconnecting adjacent strips of adjacent pairs, each of said tension springs being provided at each end with a hook which passes through one of said openings and also embraces the associated end turn of a compression spring, said openings having a width greater than the overall width of said hooks, whereby each hook can be bodily inserted through its associated opening.

3. The invention set forth in claim 1 with the addition that each of said slots is formed intermediate the length of its outer edge with a notch

receiving the hook of the associated tension spring.

4. The invention set forth in claim 2 with the addition of cross members secured to and extending between the two strips of each pair, each of said cross members extending diametrically of an end turn of a compression spring.

5. In a bed spring, a plurality of rows of coiled compression springs having their upper end turns located substantially in a common plane, a pair of spaced sheet-metal strips associated with each such row of compression springs, said pair of strips extending longitudinally of the associated row of compression springs and overlying the end turns of said springs at opposite sides of such end turns, each of said strips being provided with longitudinal slots at points where it overlies the material of the end turns of the compression springs, tension springs interconnecting adjacent strips of adjacent pairs, each of said tension springs being provided at each end with a hook which passes through one of said slots and also embraces the associated end turn of a compression spring, said slots having a length greater than the overall width of said hooks, whereby each hook can be bodily inserted through its associated slot.

6. In a bed spring, a plurality of rows of coiled compression springs having their upper end turns located substantially in a common plane, a pair of spaced sheet-metal strips associated with each such row of compression springs, said pair of strips extending longitudinally of the associated row of compression springs and overlying the end turns of said springs at opposite sides of such end turns, each of said strips being provided with openings at points where it overlies the material of the end turns of the compression springs, tension springs interconnecting adjacent strips of adjacent pairs, each of said tension springs being provided at each end with a hook which passes through one of said openings and also embraces the associated end turn of a compression spring, said openings having a width greater than the overall width of said hooks, whereby each hook can be bodily inserted through its associated opening.

7. The invention set forth in claim 5 with the addition that each of said slots is formed intermediate the length of its outer edge with a notch receiving the hook of the associated tension spring.
